DESIGN FOR AN INFANT'S SHOE

Joseph C. Teach, Piqua, Ohio

Application April 26, 1937, Serial No. 68,985

Term of patent 7 years

To all whom it may concern:

Be it known that I, Joseph C. Teach, a citizen of the United States, residing in the city of Piqua, in the county of Miami and State of Ohio, have invented a new, original, and ornamental Design for an Infant's Shoe, of which the following is a specification, reference being had to the accompanying drawing, forming part thereof.

Fig. 1 is a top view of an infant's shoe with the fastening elements on the back closed, showing my new design; and

Fig. 2 is a rear view of the shoe with the fastening elements disengaged.

I claim:

The ornamental design for an infant's shoe, as shown and described.

JOSEPH C. TEACH.
